UNITED STATES PATENT OFFICE.

MARY M. BUCKLER, OF SPRINGFIELD, MASSACHUSETTS; ALICE G. BUCKLER EXECUTRIX OF SAID MARY M. BUCKLER, DECEASED.

EYE FOR DOLLS.

Application filed June 3, 1921. Serial No. 474,640.

To all whom it may concern:

Be it known that I, MARY M. BUCKLER, a subject of the King of Great Britain, residing at Springfield, in the county of 5 Hampden and State of Massachusetts, United States of America, have invented new and useful Improvements in Eyes for Dolls, of which the following is a specification.

This invention relates to improvements in 10 toy effigies but is directed more particularly to the representation of the eyes thereof.

An object of the invention is the provision of a simple and inexpensive representation of an eye, that may be easily and quickly 15 attached to the face of the toy, thereby eliminating the necessity of the skilled labor usually required in painting or embroidering eyes upon the faces of toys.

Another object of the invention is to provide 20 an eye that comprises separate elements, that are adapted to be attached to the face of the doll in various relations to produce various facial expressions.

To this end, the invention consists in the 25 novel combination of elements hereinafter described and pointed out in the appended claims.

While the invention is here illustrated in connection with certain toys, it is obvious 30 that it is equally applicable to any other figures or effigies. The invention will be readily understood by reference to the accompanying drawings in which:

Fig. 1 is an elevational view of the head 35 of a toy effigy, having my improved representation of an eye attached thereto.

Fig. 2 is a sectional view taken on the line 2—2 of Fig. 1.

Fig. 3 is an elevational view of a fish showing 40 my invention in connection therewith.

In the drawings H represents the head of a toy effigy which, for the purposes of description is considered to be of fabric which covers a stuffing or other suitable soft substance 45 in the shape of a head.

A ring member of torus form 1 for representing the eye ball of an eye is provided and is attached to the face of the toy by stitching in the usual and well known manner. The said ring 1 is preferably circular in cross-section, the diameter of which cross section is substantially less than the diameter of the ring member. While a ring circular in cross-section is here shown and described, 50 it is obvious that other ring like shapes of

various cross-sections may be employed to produce the desired results.

A bead member 3 for representing the pupil of an eye is provided and has near its lower side, the usual thread opening through which a stitch may be passed to attach the said bead to the face f. The bead member 3 may be placed in various relative positions with respect to the ring member 1, whereby various expressions of the eye may be obtained and its diameter is considerably smaller than the inside diameter of the ring member 1. The bead member is here shown as being semi-spherical and is in thickness preferably equal to the cross-sectional diameter of the ring 1, but other bead members of various shapes and sizes may be employed as may be desired. The color of the face of the effigy is preferably such that it contrasts with the color of the ring member 75 and bead and the ring member and bead are constructed of substantially rigid material.

A fish F is shown in Fig. 3 and to which is attached, a ring member 1 and bead member 3 whereby the representation of an eye 80 is produced as in the toy effigy shown in Fig. 1.

Obviously, the ring and bead members may be attached to various toys or effigies in various relations to produce an unlimited 85 variety of expressions, and while it is preferred to employ a circular ring like member having a circular cross-section, and a semi-spherical bead member, it will be understood that members of other shapes and 90 dimensions may be employed without departing from the scope of the invention.

Having thus described the invention, what I claim is:

1. The head of a toy effigy having attached to the face thereof a ring of torus form and a bead member within said ring to represent an eye of said face.

2. The head of a toy effigy, having attached to the face thereof, a ring member 100 of comparatively small cross-sectional diameter and a bead member within said ring to represent an eye of said face.

3. The head of a toy effigy having attached to the face thereof, a ring member 105 and a bead member within said ring member to represent an eye of said face, the said bead being substantially equal in height to the cross-sectional diameter of said ring.

4. The head of a toy effigy having at-

tached to the face thereof the representation of an eye comprising a ring member having a comparatively small cross-sectional diameter and a bead member within the 5 ring having a height substantially equal to the cross-sectional diameter of the ring.

5. The head of a toy effigy having attached to the face thereof the representation of an eye comprising, a rigid ring member 10 encompassing a comparatively smaller member, the outer surface of said smaller member being substantially flush with the outer surface of said ring member.

6. The head of a toy effigy made of comparatively soft flexible material having attached to the face thereof a ring of torus 15 form and a bead within said ring to represent an eye of said face, said ring and said bead constructed of rigid material.

7. The head of a toy effigy made of comparatively soft flexible material having attached to the face thereof a ring of torus form and a substantially circular head within said ring to represent an eye of said face, 20 said ring and bead of rigid material the latter having a diameter considerably smaller than the inside diameter of the former.

8. The head of a toy effigy made of comparatively soft flexible material having attached to the face thereof a ring of torus 25 form and a bead within said head to represent an eye of said face, said ring and said bead of rigid material and having a color contrasting with the color of said face.

In testimony whereof I have affixed my 35 signature.

MARY M. BUCKLER.
